UNITED STATES PATENT OFFICE

CYNTHIA S. HARRIS, OF ROME, NEW YORK, EXECUTRIX OF LEWIS HARRIS,
DECEASED, ASSIGNOR, BY MESNE ASSIGNMENTS, TO CYNTHIA S. HARRIS.

HOISTING AND CARRYING MACHINE.

SPECIFICATION forming part of Letters Patent No. 641,508, dated January 16, 1900.

Application filed August 8, 1898. Serial No. 688,130. (No model.)

To all whom it may concern:

Be it known that LEWIS HARRIS, late a citizen of the United States of America, and a resident of Rome, Oneida county, New York, 5 did invent certain new and useful Improvements in Hoisting and Carrying Machines, of which the following is a specification.

The invention relates to hoisting and carrying machines; and it consists in the novel 10 features hereinafter more fully pointed out and claimed.

In the drawings, Figure 1 is a front or side elevation of the machine, taken from the machine as illustrated in Fig. 2 when the same 15 is reversed and supported on the ceiling or other elevated support. Fig. 2 is a bottom or lower side view of the machine looking upward when the machine is supported on the ceiling or other elevated support. Fig. 3 is 20 a view taken from the opposite side of the machine from Fig. 1 when the machine is in the position stated in the description of Fig. 1. Fig. 4 is an end view of the car and a cross-section of the track. Fig. 5 is a view 25 taken from the reverse side of Fig. 3. Fig. 6 is a front end view of the machine, taken from the left of Fig. 2. Fig. 7 is an end view taken from the right of Fig. 2. Figs. 8 and 9 are detailed views illustrating the worm-gear. 30 Fig. 10 is a vertical cross-section of the clutching mechanism, taken on line *a a* of Fig. 3. Fig. 11^a is a section taken on line *b b* of Fig. 2, and Fig. 11^b is a side view of the same. Fig. 12 represents a side view of the details of construction of a friction-clutch for holding the 35 load when the clutching mechanism is operated.

The hoist and carrier have heretofore been generally used in canning-factories where the 40 steam processing is in chests or tanks open at their tops, through which open top crates are inserted or taken out containing the cans sealed, with their contents, the crates being of the size of the opening in the steam-chest, 45 and these crates ordinarily contain from eight hundred to one thousand ordinary one-pound fruit-cans and their contents. The invention, however, is not limited to this particular use, as this system of hoist and carrier can be applied to any place or locality where it is de-

sired to elevate and carry weights in store-houses and other places.

Having described the use in general terms to which the invention can be applied, the best method of practicing the same will now 55 be pointed out.

In the drawings similar numeral references refer to corresponding parts in the several figures.

The machine is usually located on the ceiling 60 1 or other support by any suitable means of attachment, and the track 2, which in this instance is in the form of I-beam steel, (shown in cross-section in Fig. 4,) is supported on the ceiling or overhead timbers or other ele- 65 vated support. On rail 2, with flanges 3 3, Fig. 4, are mounted car-wheels or antifriction-rolls 4 between the car side walls 5 5, which wheels are mounted on the axles 6. (Illustrated in Fig. 4.) On the axles 7 7 of 70 the walls of the car are mounted grooved pulleys 8 8, Figs. 1 and 4. The car-wheels are placed on the flanges of the rail, and the car runs in either direction on the track at the will of the operator by the mechanism hereinafter more fully pointed out. The car is moved 75 backward and forward on the track through the instrumentality of the rope 9, Fig. 1. The ends of the rope are secured to the sides of the car at 10 10, Fig. 1, and pass over the 80 grooved pulleys 11 and 11^a, supported by hangers 12 12 on the ceiling or other overhead support. The grooved pulley 11^a, Fig. 2, is mounted rigidly on the shaft 13, which latter carries two beveled friction-pulleys 14 14, 85 rigidly secured thereto. The said shaft is mounted in bearings in the machine and is capable of end adjustment for throwing the face of the friction-pulleys on the shaft into and out of contact with the driving friction- 90 pulley alternately. This alternate movement is accomplished by providing diagonal opening 16, Fig. 2, in the shaft-bearing.

In diagonal opening 16 in the bearing 17 there is provided a projecting pin 15, secured 95 to a sleeve or collar (not shown) on the shaft within the bearing. The sleeve or collar should be made to fit in a groove on the periphery on shaft 13 and so arranged that the sleeve has no end motion on the shaft, while 100

the shaft is free to rotate in the sleeve or collar. The bearings 17 and 17^a are a part of the frame and are arranged to support the shaft carrying the beveled-face pulleys. On 5 the end of the sleeve or collar there is rigidly secured lever 18, so that when the lever is moved to the right or left the sleeve or collar carrying pin 15 is worked in inclined groove 16 in the bearing, the incline being at an angle to the line of the shafting and also at an angle to the line of the rotation of the shaft, so that the shaft carrying beveled pulleys is moved endwise, so as to carry pulleys 14 14 into and out of contact with the face of the 10 beveled pulley 19, which beveled pulley 19 is mounted on the end of driving-shaft 20, so that the faces of these beveled friction-pulleys can be engaged by alternating adjustment of shaft 13 through the operation of lever 18, 15 already described.

The friction driving-pulley 19, mounted on the end of driving-shaft 20, which receives power through fly-wheel 21, is always driven in the same direction. On the driving-shaft 20 are mounted, loosely, two gears 22 22^a. On 25 the inner vertical faces of the hubs of these two gears there is provided clutching mechanism, which in this instance is composed of notches 23 23, which are provided to engage 30 corresponding notches on the vertical end of the rotating reciprocating clutch 24, which is held on the shaft 20 by a spline or feather 25 and rotates with the shaft and at the same time can be moved in the direction of the 35 length of the shaft by lever 26, to which it is secured in a way not to interfere with its rotation, so that when lever 26 is moved to the right, Fig. 3, the vertical clutching mechanism on the hub of the clutch and the loose 40 gear 22^a are brought together and motion is imparted to the said gear and communicated to a corresponding gear on the shaft 27, lying parallel to shaft 20, and when the lever is moved to the left of Fig. 3 the vertical clutching 45 mechanism on the end of the clutch and the loose gear are brought together and motion is imparted to gear 22, which communicates and connects with an intermediate gear, which will be more fully described later on. By 50 sliding the clutch in either direction on the shaft 20 the ratcheted ends are brought into engagement with the corresponding ratchets on the hub for clutching the loose gears with the clutch which always rotates with shaft 55 20. By this alternating movement on the shaft a reverse motion is imparted to the parallel shaft 27. The gears 22 and 31 do not engage each other, but power is communicated through intermediate gear 28, mounted 60 on support 29, forming a part of the frame. The gear 28 meshes into gear-wheels 22 and 31, and by this method a reverse motion is imparted to shaft 27 whenever the clutching mechanism is moved to the left to engage with 65 gear 22, and when the clutching mechanism is moved toward the right into engagement with gear 22^a a reverse power is applied to gear 31^a

on shaft 27, so that by reciprocating the clutch on the shaft an alternate reverse motion is imparted to shaft 27 through the mechanism 70 already described. When the clutching mechanism is in the position shown in Figs. 2 and 3, the shaft 27 remains idle and shaft 20 continually rotates; but when the clutching mechanism is brought into engagement with either 75 of the idle gears motion is imparted to shaft 27, and that motion is capable of being alternately reversed by shifting the clutching mechanism into and out of contact with the idle gears.

The shaft 27 is mounted in suitable bearings on the frame, and to this shaft is rigidly secured gear-wheel 31, which meshes into the intermediate gear 28, which also meshes into gear-wheel 22. A gear-wheel 31^a is also mounted on the same shaft and rigidly secured thereto, said gear meshing into gear 22^a on the main driving-shaft. On shaft 27 a worm or spiral gear 32 is formed. (Best illustrated in Fig. 8.) In connection with this worm gear or shaft 32 90 a gear-wheel 33 is rigidly mounted on shaft 34, so that whenever the rotation of shaft 27 is reversed the gear 33 is also reversed, and on the end of shaft 34 a grooved drum 35 is mounted and over which the hoisting-cable 36 is 95 wrapped and on which it runs, cable 36 being secured at one end of the track, as best illustrated at 37, Fig. 1. This cable runs from this attaching-point over pulley 8, and between pulleys 8 8 on the cable the loose pulley 38^a 100 is placed, said pulley carrying hook 39, which is hooked into the load to be hoisted and carried. By shifting the clutching mechanism on the driving-shaft 20 the load can be lowered or raised at the will of the operator through 105 the mechanism which has already been described. The load may be carried on the track in either direction by operating lever 18 in either direction, by means of which friction-pulleys 14 14 can be alternately adjusted 110 into or out of friction contact with driving-clutch 19 on the driving-shaft, and the movement of the car can be regulated in either direction and any desired location by operating lever 18 either to the right or to the left, 115 depending on the direction in which it is desired to carry the load, and the moment the load arrives at the proper place by moving the friction-pulleys 14 14 out of contact with the driving friction-pulley the movement of the 120 load can be arrested.

Automatic mechanism for arresting the movement of the load is also provided. This automatic mechanism consists in mounting on the end of shaft 34 the beveled gear 40, 125 Figs. 2 and 3, which engages the beveled gear 41, rigidly secured to a stem provided with screw-threads at 42, which screw works in sliding stop 43. (Best illustrated in Figs. 2 and 3.) This stop slides in guides of the frame, so 130 that it may be driven in either direction by the screw-threaded stem into or out of contact with lever 26, which drives the lever carrying the clutch out of contact with the gear on the

driving-shaft and arrests the movement of the load. The stop 43 is moved in or out of contact with the lever 26 by the reverse mechanism already described.

5 The rope 9 should be wrapped on groove-pulley 11^a a sufficient number of times to secure proper friction on the pulley to move the load. The cable 36 must be secured on the drum 35 sufficiently strong to carry the load 10 desired. A variety of changes will readily suggest themselves to one skilled in the art without departing from the spirit of the invention.

Referring to Fig. 12, there is illustrated the 15 friction device for holding the load in an elevated position when the clutching mechanism is moved into the position shown in Fig. 2. To accomplish this, there is mounted rigidly on shaft 27^a, Fig. 12, a wheel which is illustrated in dotted lines in Figs. 2 and 3. On the under side of bearing 29 there is attached lever 29^a by means of a set-screw 29^b, which is tapped into bearing and so arranged that the lever can move freely on the set-screw, 25 and in this instance the lever has a reverse spring-curve 29^c, the lower portion of the curve passing over friction-pulley 27^a and has attached to its free end a cable 27^d, so located that it is within the reach of the operator. 30 When it is desired to hold the load in an elevated position, the operator pulls down on cable 27^d, which brings the surface of the lever into contact with wood pulley 27^a on the shaft, thereby creating sufficient friction to 35 hold the load while the clutching mechanism for reversing the power is shifted.

Having thus described the invention in a manner which will enable others skilled in mechanical construction to build and operate the same, what is claimed is—

1. The track, the car, the cable, a shaft having a spiral gear secured thereto, and two gear-wheels mounted and held thereon, the driving-shaft with two loose gears, the loose 45 gears provided with clutch-engaging hubs, the intermediate gear, the worm-gear and cable-drum on the same shaft in combination with the rotating and sliding clutch and means for operating the same, for the purposes stated.

2. The track, the car, the cable, the driving-shaft having loose clutching-gears thereon, the reversible shaft with gears rigidly secured thereto and having a worm-gear and 55 cable-drum on the same shaft, an intermediate gear in combination with movable clutching mechanism for engaging and operating the loose gear alternately, substantially as set forth for the purposes stated.

60 3. The track, the car, the cable secured at its opposite ends to the opposite ends of the car and passing over grooved-face pulley, in combination with reversing mechanism consisting of two beveled pulleys mounted on an 65 adjustable shaft, a beveled driving-pulley mounted between the two beveled-face pulleys, with means for moving the two beveled

pulleys into and out of contact with the driving-pulley, clutching mechanism for engaging and disengaging the operative gear and means 70 for operating the parts, substantially as set forth.

4. The track, the car, the pulleys located at the limit of the track, one pulley connected with the power and the other pulley being independent, the cable connected to the car, and extending over the pulley, the shaft carrying one of the pulleys, the plain beveled friction-pulleys mounted on the adjustable pulley-carrying shaft, the plain beveled friction 80 driving-pulley mounted between the adjustable pulleys, in combination with mechanism substantially as set forth, for moving the shaft and pairs of plain beveled friction-pulley into and out of contact with the plain beveled 85 friction driving-pulley substantially as set forth for the purposes stated.

5. The driving-shaft having thereon a pair of loosely-mounted gears with clutching-hubs, a shaft having a spiral gear thereon, and a 90 pair of gears secured to, and rotating with the shaft, the third gear meshing into the gear on each shaft, the shaft having a cable-drum and a worm-gear mounted thereon, a rotary sliding clutching mechanism movable in the 95 direction of the length of the shaft and rotating with the shaft, a beveled driving-pulley on the driving-shaft and mechanism for operating the sliding clutch, beveled pulleys on an adjustable shaft and mechanism for adjusting the pulleys in and out of engagement with the driving-pulley, substantially as set forth, for the purposes stated.

6. The driving-shaft having a pair of gears loosely mounted thereon with clutching-hubs, 105 a second shaft having a spiral gear thereon, and a pair of gears secured to and rotating with the shaft, a third gear meshing into gears on each shaft, a shaft having a cable-drum and a worm-gear and a beveled gear 110 rigidly secured to and moving with the shaft, a sliding clutch on the driving-shaft rotating therewith, means for operating the sliding clutch in combination with a beveled gear having a screw-threaded stem and a sliding 115 catch operated by the screw for moving the clutch out of engagement with the lever, substantially as set forth for the purposes stated.

7. The combination with track, car and rope, of the shaft adjusted in the direction of its 120 length, having two plain beveled friction-pulleys mounted thereon, a plain beveled friction driving-pulley mounted between the plain beveled friction-pulleys on the adjustable shaft, and mechanism for adjusting the 125 shaft endwise, for the purposes stated.

8. The track, the car and cables operated on the pulleys and drum, in combination with the adjustable shaft carrying a beveled pulley, a pair of beveled friction-pulleys rigidly 130 secured thereto, mechanism for end adjustment of the shaft, a driving-shaft having a beveled friction-pulley rigid thereon and two loose clutching-gears, a sliding clutch splined

- on the driving-shaft and joining clutch, sliding mechanism for engaging the loose gears, mechanism for operating the clutch, a shaft having a spiral gear thereon and two gears secured to and rotating with the shaft, an intermediate gear meshing into the gears on the two shafts, a shaft having a cable-drum and worm-gear, substantially as set forth, for the purposes stated.
10. 9. In a hoisting and carrying machine the combination of the car and connecting mechanism, the gears and sliding clutch on the driving-shaft, the plain beveled driving-pulley, the adjustable plain beveled friction-pulleys mounted to alternately engage the face of the plain beveled driving-pulley, with means for operating the parts substantially as set forth.
10. In a hoisting and carrying machine, the combination of the car and connecting mechanism, the gears, the sliding clutch, the plain beveled pulleys, the plain beveled driving-pulley mounted between the plain beveled adjustable pulleys, on opposite sides of the driving-pulley, with means for moving the plain beveled adjustable pulleys into and out of engagement with the driving-pulley, substantially as set forth.
11. In a hoisting and carrying machine, the combination of the track, car and its connect-

ing mechanism, and a plain rotating beveled driving-pulley, a pair of adjustable plain beveled friction-pulleys mounted to be alternately adjusted for engaging the driving-pulley, and a friction-brake for the purposes 35 stated.

12. A hoist provided with mechanism for reversing the travel of the load, in combination with a track, a car provided with grooved pulleys or sheaves mounted upon the car, a 40 grooved pulley mounted at the end of the travel of the car and a pulley at the other end of the travel of the car, said last-mentioned pulley being mounted on a shaft on which are mounted two beveled friction-pulleys for reversing the travel of the pulley mounted on the shaft, and a cable attached at its ends to the opposite ends of the car, the said cable running over the pulleys mounted at the extremity of the travel of the car, and being attached or secured to the pulley of the friction-pulley shaft for reversing the travel of the car, substantially as set forth for the purposes stated.
